JOHN O. FOSTER, OF PECULIAR, MISSOURI, ASSIGNOR OF ONE-THIRD TO ABIA J. SHARP, OF HARRISONVILLE, MISSOURI.

SAFETY-GEARING FOR DRILLS.

1,080,334.

Specification of Letters Patent.

Patented Dec. 2, 1913.

Application filed April 2, 1913. Serial No. 758,330.

To all whom it may concern:

Be it known that I, JOHN O. FOSTER, a citizen of the United States, and a resident of Peculiar, in the county of Cass and State of Missouri, have made certain new and useful improvements in safety-gearing for drills of the type known as dropping-drills, my purpose being to enable the drill when raised by a cable and dropped—say to the bottom of a well—to make its stroke without shocking the gearing to such an extent as to jeopardize the safety of the gearing.

As is well known in the art of earth drilling and boring, holes in the earth are frequently made by raising and dropping a drill by aid of a rope or cable which is partially wound upon a drum, and by aid of a speeding lever the cable is slackened and the drill drops, making its stroke for the purpose of making or deepening the hole in the earth.

In operating drills of the kind above mentioned, it is desirable to use a metallic cable in connection with the drill owing to the great strength afforded by such a cable. Since, however, a metallic cable has but slight extensibility, the use of such a device frequently sets up dangerous strains in the gearing employed for winding the cable and lifting the drill.

What I seek to do, therefore, is to provide cushioning mechanism interposed between relatively movable parts of the winding mechanism, and so arranged that when the drill is dropped, the shock upon the gearing is cushioned and the consequent damages to the gearing are reduced to a minimum.

Reference is made to the accompanying drawing forming a part of this specification, and in which like letters indicate like parts.

Figure 1 is a section through the winding shaft, the winding drum and the gearing used for actuating the drum. Fig. 2 is a section on the line 2—2 of Fig. 1, looking in the direction of the arrow. Fig. 3 is a detail showing in elevation the power disk through which power is communicated to the winding shaft. Fig. 4 is a diagrammatic side elevation showing the safety gearing as used in connection with the speeding lever for actuating the drill cable.

Revolutionarily supported by bearings 4, 5, is a winding shaft 6; secured rigidly upon this shaft is a winding drum 7. A metallic cable 8 is connected with this drum and

partially wound upon the same. A portion 8^a of this cable engages a pulley 9 and passes underneath the same, said portion of the cable extending through various guiding members, and being connected with the drill 60 in the usual or any desired manner.

A gear wheel 10 is provided with a hub 11 and with spokes 12, these parts being integral. Each spoke 12 is provided with a widened portion 13 integral with it and constituting a spring seat. Each spoke 12 is further provided with a boss 14 mounted centrally of the widened portion 13. I provide a number of spiral compression springs 15, and fit one end of each spring over one 70 of the bosses 14, so that each spring at one of its ends rests against the spring seat 13.

A power disk is shown at 16 and is provided with a hub 17. This power disk is rigidly secured upon the winding shaft 6 by aid of a key 18, and is provided with a number of lugs 19. These lugs are integral with the power disk 16 and extend laterally from it. Each lug 19 has a spring seat, and is provided with a boss 20 which extends 80 into the adjacent end of a spring 15, as indicated in Fig. 2. A gear pinion 21 is mounted rigidly upon a driving shaft 22 by aid of a key 22^a and is provided with teeth which mesh with the teeth of the gear 10. 85

A speeding lever 23 is employed for actuating the cable in order to lift and drop the drill. The speeding lever is mounted upon a pivot pin 24 and carries a roller 25, the latter being in engagement with the cable. 90 A revoluble crank arm 26 carries a pair of rollers 27 and as the crank arm is turned, in the direction indicated by the arrow in Fig. 4, the speeding lever 23 is alternately pressed downwardly and released, its upward movement being comparatively abrupt owing to the close proximity of the rollers 27 to the pivot pin 24.

The operation of my device is as follows: The parts being assembled and arranged as 100 above described and the cable being connected with a drill, the shaft 22 is turned in a clockwise direction according to Fig. 4 so as to lower the drill to the bottom of a well or drill hole as the case may be. This being done, the shaft 22 is secured in order to prevent it from retrograding and the crank arm 26 is now rotated as above described. The rollers 27 are brought into engagement with the speeding lever 23 and the 105 110

latter is pressed downwardly and as the crank arm continues to turn the speeding lever is released. In this manner the cable is alternately pulled upon and released—
5 that is tightened and slackened—so that the drill is lifted and dropped continuously. Experience shows that the lifting and dropping of the cable throws severe strain upon the gearing ordinarily employed but with
10 my improved safety gearing the shocks due to sudden tightening and relaxation of the cable, are taken up or cushioned by the springs 15. If, for instance, owing to the dropping of the drill a sudden strain is
15 thrown upon the cable the drum 7 is suddenly turned to a slight extent by the pull of the cable, and motion is transmitted through the shaft 6 and disk 16 to the springs 15. Again, the sudden relaxation
20 of the tension of the cable may cause the drum 7 to rock slightly and thus turn the shaft 6 to a small extent in a contra-clockwise direction according to Fig. 2. The springs 15 being under partial tension are
25 free to become slightly elongated and in so doing they cushion the shock. In this manner all injury to the gearing is prevented owing to the cushioning effect of the springs 15.
30 I do not limit myself to the precise construction shown as variations may be made therein without departing from the spirit of my invention, the scope of which is commensurate with my claims.

35 I claim;

1. The combination with a flexible member for lifting and dropping a drill, and a speeding lever for pulling and releasing said flexible member, of a drum for winding said flexible member, gearing for turning said drum, and spring mechanism connected with said gearing for alleviating shocks otherwise transmitted from said flexible member through said drum to said gearing.
45

2. In a safety gearing for drills, the combination of a cable for lifting and dropping a drill and a speeding lever for pulling upon said cable and releasing the same in order
50 to actuate said cable, a drum upon which said cable is partially wound, a revoluble

gear member connected with said drum for turning the same, and spring mechanism interposed between said drum and said gear member for preventing the transmission of 55 shocks from said cable through said drum to said gear member.

3. In a safety gearing for drills, the combination of a cable for lifting and dropping a drill, a speeding lever provided with 60 a portion for engaging said cable in order to actuate the same, a revoluble drum connected with said cable for the purpose of winding the same in order to raise and lower said drill, a shaft connected rigidly with 65 said drum, a power disk mounted rigidly upon said shaft and provided with lugs, a gear wheel loosely mounted upon said shaft and provided with spring seats, springs engaging said spring seats of said gear wheel 70 and also engaging said lugs of said power disk, and means for turning said gear wheel.

4. A device of the character described comprising a cable for lifting and dropping a drill, a speeding lever provided with a 75 portion for engaging said cable in order to actuate the same, a drum connected with said cable and adapted to be turned for the purpose of winding and unwinding said cable, a shaft connected rigidly with said 80 drum, a power disk mounted rigidly upon said shaft, a revoluble gear member located adjacent to said power disk, spring connections extending from said gear member to said power disk and means for turning said 85 gear member.

5. The combination of a revoluble shaft, a winding drum mounted thereupon, a cable connected with said drum and adapted to be wound and unwound as said drum and said 90 shaft are turned back and forth, a gear member loosely mounted upon said shaft, a driving member secured rigidly upon said shaft, springs connected with said gear member and with said driving member for 95 transmitting rotary motion from said gear member to said driving member, and means for turning said gear member.

JOHN O. FOSTER.
